UNITED STATES PATENT OFFICE

99,496

DESIGN FOR A COMBINED CIGARETTE CASE AND LIGHTER OR THE LIKE

William F. Bowen, North Attleboro, Mass., as-
signor to Evans Case Company, a corporation
of Massachusetts

Application February 7, 1936, Serial No. 61,035

Term of patent 3½ years

To all whom it may concern:

Be it known that I, William F. Bowen, a citizen of the United States, residing at North Attleboro, county of Bristol, and State of Massachusetts, have invented a new, original, and ornamental Design for a Combined Cigarette Case and Lighter or the Like of which the following is a specification, reference being had to the accompanying drawing, forming a part thereof.

The figure is a perspective view of a combined cigarette case and lighter in an open position, showing my new design.

When closed the case is of conventional form and generally rectangular in shape as indicated in the drawing, but the dominant feature of the design lies in the arrangement of the interior compartments associated with a lighter in an intermediate plane as shown.

I claim:

The ornamental design for a combined cigarette case and lighter or the like as shown and described.

WILLIAM F. BOWEN.
